UNITED STATES PATENT OFFICE

142,486

DESIGN FOR A PIN OR SIMILAR ARTICLE

Marc I. Koven, Brooklyn, N. Y.

Application May 2, 1945, Serial No. 119,349

Term of patent 7 years

(Cl. D45—19)

To all whom it may concern:

Be it known that I, Marc I. Koven, a citizen of the United States, residing at Brooklyn, in the county of Kings, city and State of New York, have invented a new, original, and ornamental Design for a Pin or Similar Article, of which the following is a specification, reference being had to the accompanying drawing, forming part thereof.

In the drawing:

Fig. 1 is a plan view of a pin showing my new design;

Fig. 2 is an edge view thereof.

I claim:

The ornamental design for a pin or similar article, substantially as shown.

MARC I. KOVEN.
